UNITED STATES PATENT OFFICE.

SYDNEY DILLON, OF EDGEWOOD, PENNSYLVANIA.

METAL-TRANSFER APPARATUS.

965,282.

Specification of Letters Patent. Patented July 26, 1910.

Application filed May 9, 1907. Serial No. 372,712.

To all whom it may concern:

Be it known that I, SYDNEY DILLON, of Edgewood, Allegheny county, Pennsylvania, have invented a new and useful Metal-Transfer Apparatus, of which the following is a full, clear, and exact description, reference being had to the accompanying drawings, forming part of this specification, in which:

10. Figure 1 is a plan view showing my improved apparatus; Fig. 2 is a sectional end view of the same; Fig. 3 is a detail view showing the jaw clutch in its disengaged position and showing the clutch-operating mechanism forming part of my invention; 15 and Fig. 4 is a similar view on a larger scale showing the clutch-operating mechanism.

My invention relates to apparatus employed in transferring rolled metal blanks of considerable length and weight such as rails, billets, blooms, etc., and the object of the invention is to provide means for transferring such blanks and improved means by 25 which such transfer mechanism is actuated.

A further object of the invention is to provide improved means by which the lifting arms for any one of a series of receiving or cooling beds located at different points in 30 the length of the feed table may be operated by means of a single motor and to provide means whereby the lifting arms when set in motion by the operator are automatically caused to raise and then lower and to 35 remain in their lowered position until the clutch-operating mechanism is again started by the operator.

In the drawings, 2 represents the skids of one of the receiving or cooling beds, 3 the 40 rollers of a roller feed-table for delivering material along one side of the cooling beds and 4 represents the rollers of a feed-table by which the material is taken from the opposite side of the cooling beds. The feed-table rollers are driven in the usual manner through suitable gears and shafts (not shown) by means of any desired type of motor.

Each of the cooling beds is provided with 50 lifting arms 5 by means of which the metal rails, blooms or other materials are transferred from the feed rollers 3 to the skids 2 forming the bed. The arms 5 of each of the cooling beds are pivoted on a lifting arm shaft 6 which is mounted in suitable bearings 7 and each of the arms 5 has a depend-

ing cam-lever or arm 8. Mounted in bearings 9 and located beneath and to one side of the lifting arm shaft 6 is a cam-shaft 10 and keyed or otherwise secured to this shaft 10 at points opposite the depending cam-levers 8 are eccentrics or cams 11 which contact with and actuate the depending arms 8 and lifting-arms 5 when the shaft 10 is rotated. Secured to one end of the shaft 10 so as to be longitudinally movable on the shaft is one of the oppositely facing clutch-disks 12 and 13 which form the clutch by which the shaft 10 is detachably secured to the clutch shaft 14. The clutch disk 13 is secured to the clutch shaft 14 which is mounted in the bearings 15 and which is provided with a driving gear wheel 16.

The inner face of the clutch disk 12 which is secured on the end of the cam shaft 10 so as to rotate with and also to be longitudinally movable on this shaft is provided with jaws 17 which engage with similar jaws 18 on the opposite clutch disk 13. Around the jaws 17 on the clutch disk 12 is an annular surface portion 19 which is plane, and surrounding the plane portion 19 is an annular cam surface 20. Mounted so as to be longitudinally movable in a bracket bearing 21 is a pin or shaft 22 having an anti-friction roller 23 rotatably secured to its lower end. The roller 23 contacts with the surfaces 19 and 20 on the inner face of the clutch disk 12 to move and hold the jaws 17 out of engagement with the similar jaws 18 on the clutch disk 13. The upper end of the vertically movable pin 22 is connected by links 24 with the lever 25 which is provided with a counterweight 26 and one end of this lever is pivoted on the bracket 27 located on the upper end of the bracket-bearing 21, its opposite end being secured by a flexible connection to the operator's hand lever, (not shown).

The clutch disk 12 is moved longitudinally on the cam-shaft 10 and into engagement with the clutch disk 13 by means of the yoke 28, the forked arms of which are provided with anti-friction rollers 29 which contact with the outer surface 30 of the clutch disk 12. The yoke 28 is pivoted on the shaft 31 and on the end of this shaft is a counterweight lever 32 on which the counterweight 33 is adjustably secured. The clutch driving gear 16 on the shaft 14 meshes with the gear 34 on the counter shaft 35 and this counter shaft is driven through the gear

2
35' by the pinion 36 located on the armature shaft 37 of the motor 38. Preferably an electric motor is used for operating the arm lifting mechanism although an engine or other rotary motor may be employed for this purpose.

In the operation of my improved apparatus the rails, billets or other materials are moved along the rollers 3 of the feed table 13 until they are opposite the skids 2 and above the lifting-arms 5 of the cooling bed on which they are to be deposited. Two or more rails may be transferred from the roller table to the cooling bed at one lifting 15 operation or the rails may be transferred singly if desired. The motor 38 is started to rotate and the rail or rails are then moved on the feed rollers 3 to a point above the lifting-arms 5 of the cooling bed to which the materials are to be transferred. When 20 the rails are in position, the operator, by means of the operating hand lever through the flexible connection and lever 25 lifts the pin 22 and the roller 23 secured to its lower end until this roller is out of engagement 25 with the clutch disk 12. When the roller 23 is clear of the disk the counterweight 33 through the shaft 31 and yoke 28 causes the clutch disk 12 to move on the cam shaft 10 until the jaws 17 engage with the jaws 18 on the oppositely facing clutch disk 13. The motor 38 through the clutch then causes the cam shaft 10 and the cams 11 to rotate and the cams contact with and raise the depending arms 8 and lifting-arms 5 until the lifting-arms are in the position shown dotted in 35 Fig. 2. As the lifting-arms 5 are tilted the rails which are above them on the feed-rollers 3 are lifted on the arms and when these arms have been raised to a point at or above 40 the angle of repose the rails will slide along the upper surface of the arms and will be deposited on the skids 2 of the cooling bed. As the cams 11 are moved through the second 45 half of their revolution the lifting-arms 5 are lowered until they reach the position shown by full lines in Fig. 2. When the operator has lifted the roller 23 on the pin 22 until it is out of engagement with the disk 12 and the counterweight 33 has automatically moved the disk 12 on its shaft to bring the jaws on the clutch disks into engagement, the pin 22 and its roller 23 is in the position shown by full lines in Fig. 4. 50 As the cam shaft 10 is moved through its revolution the roller 23 by engagement with the cam surface on the inner surface of the clutch disk 12 automatically moves this disk out of engagement with the clutch disk 13 on the shaft 14 and holds the disk 12 in its disengaged position until the operator again lifts the pin 22 and the roller 23 so as to permit the clutch disk 12 to be again moved on the shaft 10 into engagement with the clutch disk 13. After the lifting-arms have

been raised and lowered another rail or rails are brought into position above these lifting arms and the above described operation is repeated.

The lifting mechanism may be employed 70 in transferring materials from one bed to another, and from a bed to a feed-table, and may also be used in transferring from a feed table or bed into cars, and may be applied to many other uses within the scope of 75 my invention. The lifting-arms for a number of cooling beds may be simultaneously raised to deposit rails on each of the cooling beds or one cooling bed may be filled before the operation of depositing rails on 80 other of the beds is commenced.

Instead of employing one cam shaft 10 which moves the lifting arms on a series of cooling beds, each of the cooling beds may be provided with a separate cam shaft 10 85 and clutch mechanism in which case each of the cam shafts will be driven through its cam shaft gear 16 which will mesh with a suitable gear on the counter-shaft, this counter-shaft being geared to and constantly rotated by the motor 38.

The advantages of my invention will be apparent to those skilled in the art. The apparatus is simple and is easily kept in repair. One motor is employed to operate the 95 lifting-arms for a series of cooling beds. By employing a rotary motor for operating the lifting-arms, the use of a fluid pressure motor is avoided. When the lifting mechanism is started by the operator, the arms 100 are automatically raised and lowered and are kept in their lowered position until again set in motion by the operator.

I am the first to apply a rotary motor for use in operating the lifting arms of a transfer apparatus and am also the first to apply the automatic clutch operating mechanism to such apparatus and I intend to cover the same broadly in the claims.

Modifications in the construction and arrangement of the parts may be made. The lifting arms may be raised by direct contact with the eccentrics or cams and other changes may be made within the scope of my invention.

115
I claim:

1. The combination of feeding-in rolls arranged to feed work longitudinally, a receiving bed, arms oscillating about a pivot arranged to transfer work laterally from the line of feed of the feeding-in rolls, a motor adapted to operate continuously, and means associated with the motor and arms to oscillate the arms about the pivot, as the motor operates.

2. The combination of feeding-in rolls arranged to feed work longitudinally, a receiving bed, a rock-shaft disposed between the feeding-in rolls and the receiving bed, arms carried by the rock-shaft and oscillat-

ing between the feeding-in rolls and the receiving bed, in a direction transverse to the line of feed of the feeding-in rolls, a crank arm upon the rock-shaft, a cam shaft having 5 a cam working against the crank arm, a motor adapted to operate continuously, and controlling means to connect and disconnect the motor and cam shaft.

3. The combination of feeding-in rolls arranged to feed work longitudinally, a receiving bed, oscillating arms arranged to transfer work laterally from the line of feed of the feeding-in rolls, a motor adapted 10

to operate continuously, and means associated with the motor and arms to oscillate the arms as the motor operates, said means including a cam working against a crank arm, and means for connecting and disconnecting the cam and the motor.

In testimony whereof, I have hereunto 20 set my hand.

SYDNEY DILLON.
